VARIABLE VOLUME SUITCASE

George J. Hilbert, Utica, N. Y., assignor of one-half to Charles A. Heaton, Utica, N. Y.

Application July 31, 1946, Serial No. 687,253

4 Claims. (Cl. 190—47)

1

This invention relates generally to improvements in suit cases or luggage, but more particularly to a suit case which is adjustable to different lengths and thereby serves to take the place of three standard size suit cases.

It has for one of its objects to provide a self-contained sectional suit case which is so designed and constructed that it can be readily and easily adjusted by the user to any standard size desired, say to simulate either an 18-inch, 21-inch or 24-inch suit case, and which is balanced in all positions thereof.

Another object of the invention is to provide a self-adjustable suit case of this character which is neat in appearance, light in weight, compact and inexpensive in construction, and which embodies effective means for latching the case in its different positions of adjustment.

Other features of the invention reside in the construction and arrangement of parts herein-after described and particularly pointed out in the appended claims.

In the accompanying drawings:

Figure 1 is a perspective view of the suit case as it appears in its smallest, adjusted size. Figure 2 is a perspective view thereof as it appears in its largest adjusted size. Figure 3 is a perspective view of the case shown in Figure 2, but in its open position ready for packing. Figure 4 is a detached perspective rear view of the middle or main body section of the case, but omitting an interior front wall guide panel. Figure 5 is a detached perspective view of one of the end sections of the case. Figure 6 is a horizontal section taken in the plane of line 6—6, Figure 7, with the case adjusted to its intermediate size. Figure 7 is an enlarged cross section taken on line 7—7, Figure 3. Figure 8 is a similar fragmentary cross section taken in the plane of line 8—8, Figure 3, but with the cover sections closed.

Similar characters of reference indicate the corresponding parts throughout the several views.

In the preferred embodiment of my invention shown in the drawings, the same comprises a main central or middle section 10 which is of rectangular cross-section and tubular in form, and end sections 11, 11 which are substantially box-like in form and are telescopically fitted in the opposite ends of the central section for longitudinal adjustment relative thereto to vary the length and capacity of the case. These sections may be made of any appropriate material and suitably covered both exteriorly and interiorly thereof, with the interior provided with custom-

2

ary pockets and other appurtenances common to the luggage art.

The main or central section 10 of the suit case is composed of a body 12 of substantially U-shape in cross-section to provide a bottom and side walls, and a companion cover 13 of like shape, but shallower, hinged at 14 to the rear wall of such body as shown in Figure 4. This main section is also provided with the customary hardware employed for carrying and latching purposes, a handle 15 being attached to the top side wall of the body 12, while pivoted catches 16 and companion, latching plates 17 are applied to the adjoining top sides of the cover 13 and body, respectively.

The end sections 11, 11 which nest or telescopically fit within the opposite ends of the central section 10 and form end closures therefor are each composed of a body 18 of substantially U-shape in cross-section to provide a bottom, sides and an end wall, and a companion cover 19 of like shape, but shallower, hinged at 20 to the rear wall of such body, as shown in Figure 5, and adapted to swing in the same plane as the cover 13 of the main section. The bodies of these end sections nest within the companion body 12 of the central section while the covers 19 thereof nest within the cover 13 of such central section, as shown in Figures 2, 3, 7 and 8. The inner or opposing ends of the end sections are open to provide or establish open communication with the central section, and such end sections constitute the ends of the adjustable suit case. In the smallest size of the case, shown in Figure 1, the end walls of the end sections are substantially flush with the mating ends of the central section, while in the intermediate adjustment, shown by the dot and dash lines in Figure 2, and in the maximum size adjustment shown by full lines in the same figure, the end sections project uniformly corresponding distances beyond the opposite ends of the central section.

For the purpose of properly and effectually guiding and retaining the open ends of the end sections 11, 11 in telescopic relation to the main or central section 10, I provide the opposite side walls of the body 12 of the latter with longitudinal strips or panels 21 disposed in spaced relation thereto to provide resulting spaces 22 between which the opposing ends of the side walls of the end sections extend, as shown in Figure 6. These strips are secured centrally thereof by bolts 23 to the companion side walls of the main section, spacers 24 being provided for the desired spac-

ing. The free ends of these strips are normally flexed toward the body side walls and thereby serve to frictionally grip and properly guide the end sections in a straight path. To limit the outward travel of the end sections relative to the main section, transverse cleats 25 are applied to the contiguous opposing faces of the bottom walls of such sections, as shown in Figures 4, 5, and 6, which abut against each other in the maximum extended positions of the sections.

The means employed for retaining the end sections 11 in their respective adjusted positions consist of the cover-latching catches 17 and a longitudinal row of equi-spaced openings 26 formed in the front side wall of each end section and with which such catches are adapted to releasably interlock. The tongues 27 of these catches are of a length to extend into one or another of the companion latching openings and thereby serve the dual function of latching the cover 13 of the case in its closed position as well as latching the end sections of the case in their adjusted positions to retain them in place against endwise displacement. By this construction, the end sections are effectually held in place when the suit case is closed and carried from place to place, and when opened the sections are automatically unlatched and may be adjusted to suit the particular needs of the user. It will be understood that the covers 19 of the end sections are held closed by the cover of the main or central section.

I claim as my invention:

1. A suit case of the character described, comprising a main central section of tubular-like form including a body and a cover hinged thereto, end sections of substantially box-like form telescopically fitted in the opposite ends of said main section for adjustment relative thereto to vary the length and capacity of the case, each of said end sections being in open communication with and constituting an end closure for the main section and including a body and a cover hinged thereto to swing in the plane of the cover of the main section, and complementary means applied to the cover of the main section and to the bodies of the main and end sections for jointly releasably latching the latter in their adjusted positions relative to the main section and the respective covers in their closed positions.

2. A suit case of the character described, comprising a main central section of tubular-like form including a body and a cover hinged thereto, end sections of substantially box-like form telescopically fitted in the opposite ends of said main section for adjustment relative thereto to vary the length and capacity of the case, each of said end sections being in open communication with and constituting an end closure for the main section and including a body and a cover hinged thereto to swing in the plane of the cover of the main section, coengaging means on said main section and said end sections for limiting the outward displacement of the latter relative to the

former, and complementary means applied to the cover of the main section and to the bodies of the main and end sections for jointly releasably latching the latter in their respective adjusted positions relative to the main section and the respective covers in their closed positions.

3. A suit case of the character described, comprising a main central section of tubular-like form having opposing parallel side walls, two end sections of substantially box-like form telescopically fitted in the opposite ends of said main section for adjustment relative thereto to vary the length and capacity of the case, each of said sections including a body and a separate cover hinged thereto with the covers of the end sections disposed to nest partially or completely within the cover of the main section as determined by the adjustment of the sections, means applied to the opposing side walls of the main section in spaced coextensive relation thereto for receiving and guiding the companion opposing side walls of the telescoping end sections, and inter-engaging means applied to one of the side walls of the main section and its cover and to the adjoining side walls of the end sections for releasably latching the latter in their respective adjusted positions relative to the main section and the respective covers in their closed positions.

4. A suit case of the character described, comprising a main central section of tubular-like form, two end sections of substantially box-like form telescopically fitted in the opposite ends of said main section for adjustment relative thereto to vary the length and capacity of the case, each of said sections including a body and a separate cover hinged thereto with the covers of the end sections disposed to nest partially or completely within the cover of the main section as determined by the adjustment of the sections, and releasable catches applied to the main section and its cover for latching the same and the end section-covers in a closed position, the body of each end section having a row of openings therein with one or another of which the companion cover catch is adapted to interlock to retain such end sections in a set position of adjustment.
